UNITED STATES PATENT OFFICE.

CHARLES O. HILER, OF OELWEIN, IOWA.

GRAVITY-CONVEYER.

No. 833,326.

Specification of Letters Patent.

Patented Oct. 16, 1906.

Application filed May 9, 1906. Serial No. 315,996.

To all whom it may concern:

Be it known that I, CHARLES O. HILER, a citizen of the United States, residing at Oelwein, in the county of Fayette and State of Iowa, have invented certain new and useful Improvements in Gravity-Conveyers; and I do declare the following to be a full, clear, and exact description of the invention, such as will enable others skilled in the art to 50 which it appertains to make and use the same, reference being had to the accompanying drawings, and to the figures of reference marked thereon, which form a part of this specification.

15 This invention relates to gravity-conveyers; and the object is to provide an efficient, cheap, durable, and portable device for conveying from one place to another bricks, rocks, and many other heavy articles by the 20 action of their own weight or gravity. This and other objects I attain by the novel construction and arrangement of parts illustrated in the accompanying drawings, in which—

25 Figure 1 is a top or plan view of a portion of my brick and stone carrier or conveyer, showing both straight and curved parts of it. Fig. 2 is a side elevation of Fig. 1 with rollers omitted. Fig. 3 is an enlarged side elevation 30 of a piece of the conveyer. Fig. 4 is an enlarged side view of one of the roller-bearings, of which three are shown in Fig. 3. Fig. 5 is a sectional view on the line *a a* of Fig. 4 with a conveying-roller in diametrical section added. Fig. 6 is a diametrical section of a portion 35 of a conveying-roller cast in one piece. Fig. 7 is a view similar to Fig. 6, but with the roller formed of several parts. Fig. 8 is a diametrical section of one of the tapering rollers used where the conveyer-track curves laterally. Fig. 9 is a side elevation of a piece 40 of T-shaped rail used for track and a ball-bearing of modified construction secured thereon. Fig. 10 is a sectional view on the line *b b* in Fig. 9 with a roller added.

45 Referring to the drawings by reference-numerals, 1 designates the ground, platform, or usually a floor, upon which are placed supports 2 of such gradually-reduced height that 50 the rails 3 resting thereon form an inclined track, which when provided with rollers will allow bricks and other heavy objects to revolve the rollers, and thus move from one end to the other of the track.

55 The track consists of two parallel rails 3, secured together by transverse braces 4, and

is divided into sections which are detachably bolted together, as shown at 5 in Fig. 3, where the overlapping ends of the rails are penetrated by easily-removable bolts. 60

Upon each rail is secured by bolts, screws, or rivets 6 a series of ball-bearings 7, in which revolve the journals 8 of rollers 9 and 9^b, parallel rollers 9 being used where the track runs straight and tapering rollers, like 9^b, being 65 used where the track curves laterally.

The roller-bearings may be of the form 7, which consists of two plates bolted together at 12, whereby an annular groove 13 for the balls 14 of the ball-bearing is formed. In 70 this case the rail is formed with notches 15 to receive the ball-bearings, and the latter are formed with perforated ears 16, which are secured by bolts, screws, or rivets 6 to the margins 18 between the notches of the rails; but 75 the bearing may also be formed, as in Figs. 9 and 10, where the rail has no notches, and the ball-bearing 7^a is formed with downwardly-extending arms or cheeks 16^a, which are bolted to the rail, two cheeks being shown, while 80 a single one may also answer the purpose for conveyers doing only light work.

The rails may be of plain flat iron bars turned edge up or they may be made of angle-iron having a bottom flange like 19 in 85 Fig. 10 or of T-iron having flanges like 19 and 19^a in said view.

The body of the rollers I prefer to make of wrought-iron tubing and secure in the ends thereof malleable, cast, or steel journals 8, 90 which are formed with a plug 20 fitting tightly in the end of the tube, and is provided near its shoulder 22, with an annular recess 21, into which the very end of the tube 9 is closed, as in Fig. 7, by suitable dies, so tightly 95 that the plug can never work loose, much less get out of the tube.

In Fig. 6 is shown how the tube 9^a and the journal 8 may be cast integral. This may be done with both ends of the tube or only with one end, as in Fig. 8, where the tapering tube 9^b may have one journal cast with it and a plug secured in the other end. In either case the plug and journal may be solid or may preferably be cored out, as shown at 23. 100

In the use of the device the necessary sections of track, straight or curved, or both straight and curved, are put together and mounted on supports of suitable variation in height. The bricks, rocks, pig-iron, or other articles are then placed upon the rollers and allowed to move along to the lower end of the 110

track. Where the conveyed articles are too small to move properly upon the rollers, boxes are placed upon the rollers with the articles or goods in them; but having shown such boxes in another application, filed on April 23, 1906, Serial No. 313,150, it is unnecessary to here show them again.

Having thus described my invention, what I claim, and desire to secure by Letters Patent, is—

1. A gravity-conveyer comprising a pair of rails secured together in parallel position, ball-bearings secured at intervals upon the rails and rollers extending transversely between the rails and having journals resting in the ball-bearings; said rollers being made of wrought-iron tubes and the journals being cast and formed each with an enlarged part fitting the end of the tube tightly and having a shoulder fitting against the end of the tube.

- 20

2. A gravity-conveyer comprising a pair of rails secured together in parallel position, ball-bearings secured at intervals upon the rails, rollers extending transversely between the rails and having journals resting in the ball-bearings; said rollers being made of wrought-iron tubes and the journals being cast and formed each with an enlarged part fitting the end of the tube tightly and having a shoulder fitting against the end of the tube; it also having an annular groove near the shoulder and the edges of the end of the tube pressed into said groove.

In testimony whereof I affix my signature in presence of two witnesses.

CHARLES O. HILER.
